UNITED STATES PATENT OFFICE

JAMES T. COWLEY, OF SYRACUSE, NEW YORK, ASSIGNOR TO THE LAMSON COMPANY,
OF SYRACUSE, NEW YORK, A CORPORATION OF MASSACHUSETTS

LAUNDERING APPARATUS

Application filed February 10, 1926. Serial No. 87,349.

This invention relates to certain new and useful improvements in laundering machines.

The main object of the invention is the production of a machine adapted particularly for successively washing and drying clothes, and the machine is especially designed for household use in the successive washing and drying of delicate articles such as handkerchiefs, silk articles, linens and the like, altho capable of general use, and one advantage of the invention resides in the production of a machine which is shiftable to different positions, with means for supporting the machine in either of said positions, one of which is designed for a washing position and the other of which is designed for a drying or extracting position.

A further advantageous feature of the apparatus resides in the mechanism for driving the perforated basket or container adapted to contain the clothes, and including means for readily effecting a variation in the speed of the container or basket to adapt it to its successive uses of washing and drying in its varied positions.

A further advantage resides in the fact that the entire driving mechanism is carried by the cover of the apparatus and is readily shiftable from its position upon the tub or vat preferably combined with means for supporting the cover in its shifted position, at which it permits removal or insertion of articles treated, and if desired complete removal of the tub or perforated container or basket for the clothes, which basket is separated from connection with the driving mechanism upon removal of the cover.

Other objects and advantages relate to the details of the structure and the association and relation of the parts thereof all as will more fully appear from the following description taken in connection with the accompanying drawings, in which:

Figure 1 is a top plan view of an apparatus of this invention.

Figure 2 is a section on line 2—2, Figure 1.

Figure 3 is a section on line 3—3, Figure 50 1, showing the apparatus in dotted lines in

its position for washing clothes contained within the basket.

Figure 4 is a section on line 4—4, Figure 3.

Figure 5 is a section on line 5—5, Figure 3.

Figure 6 illustrates a method of connecting the cover-removing handle or rod to the cover. 55

Figure 7 illustrates a modified form of structure.

Figure 8 illustrates a further modified form of structure. 60

The apparatus as illustrated comprises a tiltable tub or vat —1— carried by and within a frame —2— consisting in this instance of three uprights or legs —3— spaced equal distances apart and connected at a point, in this illustration midway up the side of the vat —1— by a circular rod or bar —4—, in this instance of tubular form, as by clamping members —5—. The circular rim —4— of the frame is of a diameter adapted to receive the tub and permit its removal vertically therefrom, and a rubber or other resilient cushion —6— is provided preferably one adjacent each clamping member and of a form to seat in one of the horizontal corrugations in the wall of the tub —1— and rest upon the tube —4— to assist in supporting the tub. 75

The frame —2— also includes radial bars —7— extending inwardly from the legs and connected to a central ring —8— carrying an annular gasket —9— of rubber or other suitable material within and upon which the boss —10— secured axially to the bottom of the tub —1— rests to assist in supporting the tub. The boss —10— may be welded or otherwise secured to the reinforcing plate —11— conforming in shape to the bottom of the tub —1— and secured to the tub —1— and to a second reinforcing plate —12— arranged within the tub in any suitable manner, as by rivets —13—. An additional reinforcing disk —14— may be provided within the plate —12— and secured thereto in any suitable manner, as by welding or the like. 80

The stub shaft —15— extends through the boss —10—, the bottom of the tub and the reinforcing disks or plates —11—, —12— and —14—, and is connected securely to these members in 85 100

any suitable manner, as by nuts —16— threaded upon the end of the shaft and adapted to draw and hold the shoulder —17— upon the shaft in tight contact with the disk —14—. The shaft —15— projects upwardly within the vat —1— and is adapted to receive the hollow boss or bearing —18— which is vertically disposed and opens downwardly and has its upper end rigidly secured in any suitable manner to the bottom of the perforated clothes container or basket —19—.

As here illustrated the bottom of the basket is slightly convex at its central portion and is reinforced by the exterior plate —20— and the interior plate —21— conforming in shape to the bottom of the basket and secured to it and to the bearing —18— in any suitable manner as by rivets —22— or the like.

As the basket or clothes container —19— rides during its rotary movement upon the shaft —15—, the upper end of the shaft is preferably recessed to receive a hardened steel pin —23— upon which the hardened ball —24— in the bearing —18— rests. The stub shaft —15— constitutes the sole means for supporting the clothes container —19—, and for that reason the bearing —18— is preferably of considerable length so that the shaft constitutes a firm, substantial support which maintains the clothes container in substantially axial alignment within the vat —1—.

The clothes container as illustrated, is formed with a multiplicity of perforations —25— or openings in its cylindrical vertical wall, and is preferably divided into two similarly shaped portions by a diametrically disposed partition wall —26— also provided with a multiplicity of perforations —27— permitting communication between the two sections or portions of the clothes container. The upper end of the container —19— is turned inwardly somewhat and is formed at its edge with a bead —28— and a rod —29— extends diametrically across the container at its upper end and may be bowed downwardly somewhat at its central portion and secured at its opposite ends to the container in any suitable manner, as by rivets —30—.

The rod —29— may be aligned with and secured to the upper edge of the partition —26— as perhaps best illustrated in Fig. 2. The upper edge of the vat —1— is preferably beaded, as illustrated at —31— and is adapted to receive a cover —32— of substantially conical form and formed with an elongated axial bearing —33— at its apex. The lower edge of the cover —32— is formed with a flange —34— resting upon the upper side of the bead —31— and a vertical flange —35— extending downwardly within the upper open end of the vat —1—, whereby the cover is maintained in proper position with respect to the vat. A partition wall or plate

—95— which may, as shown, be of substantially circular outline, is secured within the conical cover —32— in any suitable manner, as by screws —36— so as to form a gear chamber —37— within the upper portion of the cover. The partition wall —95— is slightly elevated at its central portion so as to provide a surrounding annular groove, and is provided with a depending boss —38— in axial alignment with the bearing —33— at the apex of the cover. The driving shaft —39— is journaled in the anti-friction bearings —40— and —41— and the interposed bushing —42— disposed within the bearing —33— and the friction disk —44— is keyed to the tapered upper portion of shaft —39— and rests upon the upper surface of the bearing —40— and is secured upon the shaft by means of nut —45—.

The bushing —42— may be omitted, if desired, and the shaft —39— journaled directly in bearing —33— which may be of a diameter suitable for the purpose.

The friction disk —44— is adapted to be driven by a friction wheel —45— mounted upon the armature shaft —46— of an electric motor —47— preferably mounted between a pair of spaced brackets —48— secured to the cover —32— in any suitable manner, as by screws —49—, the friction wheel —45— being maintained in driving relation with the friction disk —44— in any suitable manner, as by spring —50— disposed within the tube —51— secured in the boss —52— upon the cover —32—. The spring —50— tends at all times to move the motor —47— about its pivots —53— and holds the friction wheel —45— in contact with the flat friction surface —44—, the central portion of which disk is as shown, of somewhat conical form to provide a compact structure.

The washing operation requires the use of more power than the drying operation in which the container rotates at high speed and in tilted position of the tub the motor is largely supported on the brackets and its weight removed from spring —51— so that the entire force of the spring is exerted in holding the co-operating friction surfaces together for washing, whereas in the drying operation the spring supports a considerable portion of the weight of the motor.

The friction disk and the friction-wheel —45— may be enclosed by a cap —54— in the form of substantially half a sphere having its open end fitted over the circular flange —55— extending upwardly from the cover —32—.

The lower end of the driving shaft —39— carries the driving pinion —56— in mesh with the planetary gears —57— mounted on the stub shafts —58— and disposed symmetrically upon opposite sides of the pinion. These gears are held in position between a

pair of spaced plates —59— and —60— preferably of substantially similar form as best illustrated in Figures 4 and 5, and secured together as best shown in Figure 3 by means of bolts —61— which have one end secured to the upper plate —59— and project through openings in the lower plate —60—, the projecting portions being equipped with springs —62— which lie between the heads of the bolts and the plate —60— so as to tension the plates toward each other.

Between the gears —57— and the plate —59— are positioned friction disks —63— and between the plates —60— and the gears —57— are positioned the friction disk —64—, all of these parts being held in contact with adjacent parts by means of the springs —62—.

The gears —57— are each formed in this illustration with a concentric integral gear —65— of comparatively small size that projects through the lower plate —60— so as to mesh with the comparatively large gear —66— mounted on the upper end of the driven shaft —67— which is axially disposed with respect to the driving shaft —39—. The upper plate —59— has a recess for receiving the anti-friction bearing —96— mounted on the driving shaft —39— and preferably spaced from the anti-friction bearing —41— by an interposed disk.

The plate —59— is further provided with an axially projecting flange —70— constituting a brake shoe with which the brake bands —71— are adapted to contact. These brake bands are preferably secured at one end upon pivot posts —72— secured to the cover 32 and are of arcuate form extending around opposite sides of the drum —70— with their opposite ends spaced apart and tensioned toward each other by means of spring —73—.

Normally, therefore, the brake shoes are in tight contact with the brake drum so as to resist rotary movement of the drum and the plate —59—. Means is provided, however, for spreading the brake shoes against the tension of the spring —73—, as for instance cam —74— positioned between the free ends of the brake shoes and mounted upon a shaft —75— journaled in the cover —32— and adapted to be rocked in any suitable manner as by handle —76— to rotate the cam so as to spread the brake shoes away from the brake drum to permit free rotation of the latter, or to permit the brake shoes to be drawn into tight contact with the drum by means of spring —73—.

The gear —66— rests upon anti-friction bearings —77— seated in a recess in the upper portion of the boss —38—, a small friction disk being interposed between the gear and the inner ring of the anti-friction bearing, should that be desirable. The driven shaft —67— extends through this bearing and through bushing —78—, compressible pack-

ing —79—, and gland —80—, all arranged within the boss or bearing —38—. The rear end of the bushing —78— and the forward end of the gland —80— where they contact with the compressible packing are preferably oppositely tapered so that the compressible packing is of greater axial length where it contacts with the shaft than where it contacts with the bearing —38—.

The lower end of bearing —38— is preferably externally threaded for the reception of cap —81—, spring —82— being interposed between the gland —80— and the cap —81— to maintain packing —79— in compressed condition to provide a lubricant-tight bearing.

The shaft —67— extends through the cap —81— and the driving fork —83— is secured upon the lower tapered end of the shaft as by means of nut —84—, and the fork is keyed 85 or splined to the shaft for simultaneous rotation. The prongs of the fork —83— are out of alignment and are adapted to fit upon opposite sides of the cross-bar —29— so that rotation of the driven shaft —67— will produce rotation of the clothes container —19—.

In addition to the three vertically disposed legs —3— of the framework —2—, an additional supporting leg —90— is provided which extends laterally from the vat —1—, and in Figures 1 and 3 is shown as formed in connection with the tube —4— extending outwardly and being inclined slightly downwardly therefrom and is positioned at a point centrally between two of the legs —3— and in connection with the two legs with which it is centrally arranged is adapted to constitute a support for the vat, and the apparatus when moved to an inclined position, preferably at an angle of about 45 degrees to a horizontal plane, as shown in dotted lines, Figure 3. As shown, the armature shaft —46— is disposed at substantially right angles to the lateral projection of the leg or support —90— so that the armature shaft is substantially 110 horizontal in either vertical or tilted position of the apparatus.

This inclined position of the apparatus is the washing position, and in this position the water in the tub or vat —1— is at a level above a portion of the perforations in the container —19— when the latter is stationary. When the machine is in vertical position shown in full lines, Figure 3, the water level is at a point below the perforations in the container —19— and the machine in that position is adapted for drying the clothes upon a centrifugal extraction principle.

This latter operation of drying requires comparatively high speed, while the operation of washing is effected at a considerably lower speed, and the gearing and associated apparatus heretofore described are adapted for effecting these two desired speeds of operation of the clothes container —19—.

When the cam —74— is in the position shown in Figure 4 and the drum —70— and plate —59— are frictionally maintained from rotary movement, the pinion —56— causes a rotary movement of gears —57— at a somewhat lower speed than that at which the shaft —39— rotates and the pinions or gears —65— integral with gears —57— effect a rotary movement of gear —66— and shaft —67— at a still lower speed, and this position of the cam —74— is the one at which the washing operation should be performed in the inclined position of the apparatus while it is resting upon two of the vertical legs —3— and the fourth leg —90—.

By turning handle —76—, cam —74— spreads the brake bands or shoes so that they are out of contact with the drum —70— and the drum and its carrying plate —59— are free to rotate. In this position the friction between the gears, friction disks and plates as effected by springs —62— is such that the entire gearing, plates and friction disks rotate as a unit and the speed of the driven shaft —67— is in this condition substantially equal to the speed of the driving shaft —39—.

This position of the cam —74— is the position for drying the clothes by high speed rotation of the perforated container —19—. For illustration, the armature shaft —46— may rotate at a speed of 6000 R. P. M. The friction wheel —45— and the friction disk —44— are so related that the disk is given a relative speed of approximately 1000 R. P. M. This is the speed of the driven shaft —67— and the container —19— during the drying operation when the brake drum and plate —59— are free to rotate.

When the plate —59— is maintained from rotation and the driving is effected through the reduction gearing disclosed, the speed of the driven shaft as here illustrated is approximately 40 rotations per minute, and this is the speed of operation of the clothes container of the apparatus for washing purposes in inclined position.

It will be noted that the gearing and the apparatus for driving the same is entirely carried by the cover —32—, and is separable from the clothes container —19— by merely removing the cover, and for the purpose of effecting an easy removal of the cover and supporting the same when removed, one of the legs —3— which as shown, is of tubular form, is extended upwardly above the vat encircling the rim —4— and is adapted to receive one end of a removing or supporting bar or rod —85— which is slidable within the tube constituting an extension of the leg —3—, and is limited in its downward movement by collar —86— secured in desired position upon the handle rod —85— as by set screw —87—, the position of the collar being

such as to permit seating of the cover —32— upon the beaded open edge of the vat —1—. The other end of rod —5— is turned downwardly and is positioned within an upwardly extending hollow boss —88— formed on the cover —32— and is secured to the boss in any suitable manner, as by a pin extending through the boss and the end of the rod in a somewhat loose manner so as to permit slight relative movement.

The entire cover, gearing, motor and driving parts may be removed from the vat —1— by lifting the rod —85— and may be turned away from the vat by rotation of the rod in the extension of tube —3—, and then by lowering the rod until collar —86— contacts with the upper end of the extension of the tube, the cover and driving apparatus carried thereby are supported so as to expose the entire upper open end of the container —19— to permit insertion or removal of clothes or the insertion or removal of the container itself.

Obviously, other means than the drum —70— and its brake bands, may be utilized for preventing rotation of plate —59— when desired, altho the structure disclosed is deemed preferable and when the disk is held stationary, the friction disks allow the container to gradually accelerate without slowing up the motor at the start.

In Figure 7, a modified form of structure is shown in that the reinforcing plate or disk —11— is made somewhat larger than in the previous figures, and the legs —97— are secured directly to the vat —1— of which the reinforcing plate —11— forms a part. This plate may be extended upwardly at one side so as to carry the fourth leg —91—, which in connection with two of the other legs —97—, constitutes a support for the apparatus in its inclined washing position.

In Figure 8 a further modified form of structure is illustrated in that a triangular frame —100— is utilized having three feet, the frame being open at one side and formed with upwardly opening bearings —101— on opposite sides, in which the journals or shafts —102— projecting diametrically from opposite sides of the tub —1— are mounted. The entire tub —1— and the container, cover, gearing, etc. are adapted to tilt about the journals —102— on the frame —100—. This is effected by lifting the tub upward until projection or boss —10— is removed from the gasket —9— whereupon the tub can be tilted until the boss contacts with the stop —103— on the frame to prevent further tilting movement. At this time or previously the journals 102 will have come to rest in the bearings —101—. The weight of the driving mechanism carried by the cover —32— holds the tub in tilted position for the washing operation.

Altho I have shown and described a specific structure together with the details thereof, as constituting an at present preferred form of the invention, I do not desire to restrict myself to the details of the structure or the parts thereof, as various changes and modifications can be made without departing from the invention as set forth in the appended claims.

10 I claim:

1. An apparatus of the class described comprising a tub, a clothes container rotatably supported within the tub, a framework for supporting the tub in a substantially vertical position and an additional support extending laterally from the tub and adapted to assist in supporting the apparatus in a tilted position.

2. An apparatus of the class described comprising a tub, a clothes container rotatably supported within the tub, a framework for supporting the tub in a substantially vertical position, an additional support extending laterally from the tub and adapted to assist in supporting the apparatus in a tilted position, a cover for the apparatus, and mechanism carried by the cover for driving the container in either position.

3. An apparatus of the class described comprising a tub, a clothes container rotatably supported within the tub, a framework for supporting the tub in a substantially vertical position, an additional support extending laterally from the tub and adapted to assist in supporting the apparatus in a tilted position, a cover for the apparatus, and mechanism carried by the cover for driving the container at either of two substantially different speeds.

4. A combined washer and dryer comprising a tub, a clothes container rotatably supported within the tub, a framework comprising feet for supporting the tub in a substantially vertical position and another foot projecting laterally from the framework for supporting the tub framework in a tilted position.

5. A combined washer and dryer comprising a tub, a clothes container rotatably supported within the tub, a framework for supporting the tub in a substantially vertical position, and means for supporting the tub framework at an inclination of about 45 degrees comprising a foot laterally projecting from the framework at a point above the lower end thereof.

6. A combined washer and dryer comprising a tub, a clothes container rotatably supported within the tub, a framework for supporting the tub in a substantially vertical position, means projecting laterally from the framework above the lower end thereof for supporting the tub framework in a tilted position, and a driving mechanism capable of rotating the clothes container at one speed

in its vertical position and at another speed when the tub is inclined.

7. A combined washer and dryer comprising a tub, a perforated container rotatably supported therein, a perforated wall dividing the container into two communicating sections and a driving mechanism removably engaging the upper edge of said perforated wall.

8. A combined washing and drying apparatus comprising a tub, a clothes container rotatably supported within the tub, a framework for supporting the tub in a substantially vertical position and a foot projecting laterally from the framework above the lower end thereof adapted to support the tub in an inclined position, and a single mechanism movable with the tub for driving the rotatable container in either vertical or inclined position of the tub.

In witness whereof I have hereunto set my hand this 28th day of January, 1926.

JAMES T. COWLEY.
